(57) **CLAIM**

The ornamental design for a shoe as shown and described.

DESCRIPTION

FIG. 1 is a front, top, and left side perspective view of a shoe embodying our new design.

FIG. 2 is a top and left side perspective view thereof.

FIG. 3 is a top and right side perspective view thereof.

FIG. 4 is a front and top perspective view thereof.

FIG. 5 is a bottom view thereof.

FIG. 6 is a front and bottom perspective view thereof; and, FIG. 7 is a back and top perspective view thereof.

Broken lines are used to illustrate features of the shoe which form no part of the claimed design in the current numbered figures. For example, broken lines showing the knobs, the lace cables, the components that receive the lace cables, portions of the upper near the heel, the tongue, the collar portion, the interior of the shoe, the tag inside the interior of the shoe, the sole, and the logos and lettering form no part of the claimed design in the current numbered figures. Dot-dashed broken lines are used to illustrate stitching which forms no part of the claimed design in the current numbered figures.
